Des. 218,092
Patented July 21, 1970

218,092

FOLDABLE HOME

Roger A. King and Keith O. Burton, Elkhart, Ind., assignors to Bur Kin Homes Corporation, Whitepigeon, Mich., a corporation of Indiana

Filed Aug. 14, 1969, Ser. No. 18,682

Term of patent 14 years

Int. Cl. D12—10; D25—04

U.S. Cl. D14—3

FIG. 1

FIG. 5

FIG. 2

FIG. 6

FIG. 3

FIG. 4

FIG. 1 is a front elevational view of a foldable home embodying the present design;

FIG. 2 is a side elevational view of the foldable home shown in FIG. 1;

FIG. 3 is an elevational view of the side opposite that shown in FIG. 2;

FIG. 4 is a rear elevational view;

FIG. 5 is a rear elevational view of the home shown in the preceding figures, showing the home in its folded condition; and

FIG. 6 is a side elevational view similar to that shown in FIG. 3, showing the home in its folded condition.

We claim:

The ornamental design for a foldable home, substantially as shown and described.
